UNITED STATES PATENT OFFICE

ALFRED J. CHAMBERLAIN, OF MILWAUKEE, WISCONSIN

DISPENSING CONTAINER

Application filed April 27, 1932. Serial No. 607,699.

This invention relates to a dispensing container, especially designed and adapted for use with alcohol, although also capable of advantageous use with oil and other liquids and substances.

One of the principal objects of the present invention is to provide a container of this character so constructed and organized as to greatly facilitate pouring of the contents of the container therefrom, and this in such manner that the contents will be kept out of contact with the drum. This is especially important with substances such as alcohol which are a solvent for the lacquer with which the cam is coated and labeled.

Another important object of the invention is to provide a container of this character in which the dispensing means or spout is so arranged and combined with the container as to eliminate the necessity of a vent, the plane of the opening of the dispensing means approaching the vertical at the beginning of pouring to provide for free and unobstructed communication of the space above the level of the liquid with the atmosphere at all times.

Another object is to provide a container having dispensing means which is self-draining and which is so constituted that the liquid will not drip on the side of the drum or on the floor when finishing pouring or at any other time.

Among other objects of the invention are to provide a container which may be sealed and which may not be opened without breaking the seal. This object is obtained without rendering the container liable to leak, the sealing bands being riveted to parts of the exterior dispensing means and not to the head of the drum. The cap of the dispensing means is easily opened.

Other objects and advantages reside in certain novel features of the construction, arrangement and combination of parts which will be hereinafter more fully described and particularly pointed out in the appended

claims, reference being had to the accompanying drawings, forming a part of this specification, and in which:

Figure 1 is a perspective view showing a container embodying the present invention; 50

Figure 2 is a sectional view taken on line 2-2 of Figure 1;

Figure 3 is a sectional view taken on line 3-3 of Figure 2; and

Figure 4 is a sectional view similar to 55 Figure 2 but showing a modified form of the invention.

Referring to the drawings, the numeral 1 designates the body portion of the container which may be of cylindrical form and have a 60 lower head or bottom of any suitable construction. The upper head designated at 3 is secured to the upper end of the body portion as at 4 and has a plain flat horizontal portion 5 and an inclined portion 5', the inclined portion extending downwardly and outwardly from the flat portion toward the body portion of the container. A pouring spout 6 is provided and has angle flanges 7 around its lower edge which are inter-crimped or inter-seamed with the portion 5' of the head of the container. It also has part of its upper edge beaded as at 8 and part flanged as at 9 and pressed firmly into engagement with the seam 4. The flanged portion 9 is engaged with an 70 outwardly pressed portion of the upper end of the body portion of the container so that the pouring lip that the flanged portion of the spout defines lies outwardly beyond the peripheral wall of the container. 80

The outlet opening of the container is provided with an outlet fitting or neck 10 having the form of a short tube or sleeve, the inner end of which is inter-seamed or inter-crimped with the portion of the head 3 and 85 with the portion 7 of the spout, as will be clear from the drawings. Intermediate its ends the tube 10 has a corrugation 13 and its upper end is rolled over to provide a gasket seat 14. 90

A closure 15 is provided and has a peripheral flange 16 formed with an inturned lower edge 17. The peripheral flange 16 and its inturned lower edges are provided with angularly spaced slots so that the portions between the slots may flex to permit the inturned lower edge to be snapped into locking engagement with the shoulder 18 presented by a portion of the tube 10 which defines the corrugations. A gasket G is provided in the closure cap 15. With this construction, by pressing on the center of the body portion 15, the body portion will be buckled by a snap action and the enclosure 15 may be disengaged. This is the conventional type of closure cap widely used and per se forms no part of the invention.

An inverted cup-shaped guard 19 encloses the cap and outlet fitting and where the receptacle is sealed coats with the seal. The seal is only shown diagrammatically, being designated at 20, and is associated with sealing bands 21, the ends of which are riveted as at 22 to portions of the spout.

25 As shown in Figure 4, the container with a head 3 and an inclined portion 6 may be equipped with a different type of closure. Where the container is used for oil it may be desirable to employ the dispensing structure shown in Figure 4. As illustrated in Figure 4, the outlet tube or fitting 10 is omitted and is replaced by a different type of outlet tube or fitting designated generally at 25 and consisting of a cylindrical or tubular portion 26 having threads formed therein and provided with an attaching portion 28 which is inter-seamed with the portion 5' of the head and with the spout 6. The closure in this case consists of a plug 30 which is threaded into the tube or cylindrical structure 25. In other respects this form of the invention is like that shown in Figures 1 to 3 and hereinabove described.

45 The outstanding advantage of the containers embodying the present invention, is the manner in which pouring is facilitated. The container need be but tipped slightly to discharge its contents when it is full and at this time and at all other times a well defined and easily controlled stream issues from the container. The contents dispensed are kept out of contact with the drum. There is no bubbling or gurgling and this without the provision of a vent since the plane of the outlet opening closely approaches the vertical at the beginning of pouring and free and unobstructed communication is afforded between the space in the container above the liquid 55 and the atmosphere.

While only two forms of the invention have been shown, these are merely typical or illustrative and various changes in the size, form and arrangement of the parts may be made 65 without departing from the spirit of the in-

vention and the scope of the subjoined claims.

The invention claimed is:

1. A dispensing container of the character described having the usual body portion and provided with a top formed with a portion inclining downwardly toward the periphery of the container, said inclined portion having an outlet opening, a separate spout formation interconnected with the container adjacent the outlet opening, an outlet fitting for the outlet opening, and a closure cooperable with the outlet fitting, said separate spout formation surrounding said outlet fitting. 70

2. A container having the usual body portion and having an upper end plate secured to the body portion and provided with an inclined section extending downwardly and outwardly to the periphery of the container, said section having an outlet opening, a spout inter-seamed with the periphery of the container and with the portion of the inclined section adjacent its outlet opening, an outlet fitting inter-seamed with said inter-seamed formation and extending outwardly 85 from said section with its axes perpendicular to the plane of said section and inclined outwardly with respect to the longitudinal axis of the container and a releasable closure 90 for said outlet fitting. 95

3. A container having the usual body portion and having an upper end plate secured to the body portion and provided with an inclined section extending downwardly and outwardly to the periphery of the container, 100 said section having an outlet opening, a spout inter-seamed with the periphery of the container and with the portion of the inclined section adjacent its outlet opening, and a releasable closure for said outlet opening. 105

4. A dispensing container of the character described having a body portion provided with a top formed with a portion inclining downwardly and outwardly toward the periphery of the container, said inclined portion having an outlet opening, a spout formation on the container surrounding the outlet opening, and a releasable closure for the outlet opening. 110

5. A dispensing container of the character described having the usual body portion and provided with a top formed with a portion inclining downwardly and outwardly toward the periphery of the container, said inclined portion having an outlet opening, a short tubular outlet fitting inter-seamed with the marginal edge of the inclined portion surrounding the outlet opening, said outlet fitting inclining upwardly and outwardly toward the periphery of the upper end of the body portion and a releasable closure for said outlet fitting. 120

6. A dispensing container of the character described having the usual body portion and 130

provided with a top formed with a portion
inclining downwardly toward the peripher-
ery of the container, said inclined portion
having an outlet opening, a spout formation
5 on the container adjacent the outlet opening,
an outlet fitting for the outlet opening, a
closure cooperable with the outlet fitting, a
guard for said closure, and sealing means
10 connected with the spout formation and co-
acting with said guard.

In witness whereof, I hereto affix my sig-
nature.

ALFRED J. CHAMBERLAIN.
